(57) **CLAIM**

The ornamental design for a toy animal chute, as described and shown.

DESCRIPTION

FIG. 1 is a top perspective view of the toy animal chute;

FIG. 2 is a bottom perspective view thereof;

FIG. 3 is a right side view thereof;

FIG. 4 is a left side view thereof;

FIG. 5 is a rear end view thereof;

FIG. 6 is a front end view thereof;

FIG. 7 is a bottom view thereof; and,

FIG. 8 is a top view thereof.

The broken lines showing the toy truck are for the purpose of illustrating environmental structure only and do not form part of the claimed design.
